FIG. 1

FIG. 2

Ralph T. Osman INVENTOR
BY Robert Robb ATTORNEYS

UNITED STATES PATENT OFFICE

120,014

DESIGN FOR A DIRT MOVING SCRAPER

Ralph T. Osman, Milwaukee, Wis., assignor to
Koehring Company, Milwaukee, Wis.

Application August 22, 1939, Serial No. 86,830

Term of patent 7 years

To all whom it may concern:

Be it known that I, Ralph T. Osman, a citizen of the United States and resident of Milwaukee, in the county of Milwaukee and State of Wisconsin, have invented a new, original, and ornamental Design for a Dirt Moving Scraper, of which the following is a specification, reference being had to the accompanying drawing, forming a part thereof, in which:

Figure 1 is a perspective view taken from the front of a dirt moving scraper showing my new design.

Figure 2 is a perspective view taken from the rear thereof.

I claim:

The ornamental design for a dirt moving scraper, substantially as shown.

RALPH T. OSMAN.
